COMBINATION LOCK SWITCH

Clarence M. Waite, Greenbush, Mass.

Application July 9, 1948, Serial No. 37,937

3 Claims. (Cl. 200—43)

1

This invention relates to a novel and improved combination lock switch, especially although not exclusively, for automobile ignition systems, the primary object of the invention being to provide a simplified and more serviceable device of this kind which is reliable and easy in operation, and offers substantial protection against unauthorized operation of the automobile or the like.

Another important object of the invention is the provision of a device of the above indicated character which is suitable either to replace entirely the usual key-operated automobile ignition switch or to supplement the same in such a way that with the combination lock switch in circuit closing position, the key-operated switch may be operated with its key in the usual way.

Other important objects and advantageous features of the invention will be apparent from the following description and accompanying drawings, wherein, merely for purposes of illustration, a specific embodiment of the invention is set forth in detail.

In the drawings—

Figure 1 is a top plan view.

Figure 2 is a vertical longitudinal section, taken on the line 2—2 of Figure 1.

Figure 3 is a transverse vertical section, taken on line 3—3 of Figure 2.

Figure 4 is a horizontal section, taken on the line 4—4 of Figure 2.

Figure 5 is a side elevation of the contact masking wheel.

Figure 6 is a side elevation of one of the plunger actuated wheels.

Figure 7 is a side elevation of the contact masking half-wheel and,

Figure 8 is a side elevation of one of the plunger actuated half-wheels.

Referring in detail to the drawings, the numeral 9 generally designates the casing of the illustrated device, in the form of an elongated, substantially square cross section box, open at its top and provided with a cover 10 riveted in place on a flange 11, as indicated at 12. The casing 9 is adapted to be securely mounted under the instrument panel or other suitable location in the event of use in an automobile. The opposite endwalls 13 and 14 of the casing have vertically spaced sockets 15, 16 serving as journals for the ends of parallel vertically spaced upper and lower shafts 17 and 18 located in the same vertical plane.

A return spring for returning the upper shaft 17 to starting position after operation thereof is in the form of a spring wire 19 fixed to the

2

casing sidewall 20 at 21 and terminating in a helix 22 coiled tightly around the shaft at the right hand end thereof and secured thereto. A similar return spring 23 fixed on the casing sidewall 20 at 24 is provided for the left hand end of the lower shaft 18. On corresponding ends of these shafts are fixed ratchet wheels 25 and 26, having over-riding downwardly spring-pressed ratchet dogs 27 and 28, respectively, hinged on the casing sidewall 20, whereby the upper and lower shafts are limited to rotation in one direction, in this instance the clockwise direction, as viewed in Figure 3.

Mounted through the cover 10 at equally spaced longitudinal intervals is a plurality of plunger buttons, in this instance, six such buttons, designated 1, 2, 3, 4, 5 and 6, from left to right. Each plunger consists of a button head 30 fixed to the upper end of a rod 31 extending slidably through an opening in the cover 10 and through a guide tube 32 fixed to the inner side of the cover, with a helical spring 34 expanded between the cover 10 and the head 30 and normally retracting the plunger to starting or retracted position.

As shown in Figure 2, the rod of button 1 reaches downwardly as far as the lower shaft 18, the rods of buttons 2 and 3 reach only to the upper shaft 17, the rod of button 4 reaches the lower shaft 18, the rod of button 5 reaches only to the upper shaft 17, while the rod of button 6 reaches to the lower shaft 18.

Fixed in appropriate position along the upper shaft 17 for operation by the rods of buttons 2, 3, and 5 are half-wheels 35, 36 and 37, respectively, each consisting, as shown in Figure 8, of a semi-circular disk 38 having on one side a substantially diametrical lug 39 for engagement by the lower end of the related plunger rod. As shown in Figure 3, the lugs 39 are horizontal for engagement by the lower ends of the related rods 31 when the half-wheels are in starting position. To the left of the plungers the upper shaft 17 has fixed thereon a masking half-wheel 40, devoid of a lug but formed with a hole 41 therethrough near and midway the ends of its peripheral edge, as shown in Figure 7.

Fixed on the lower shaft 18 to the left of and alongside of the masking half-wheel 40, is a masking wheel 42, formed, as shown in Figure 5 with a single hole 43 near its peripheral edge, in position to come into axial alignment with the hole 41 in the masking half-wheel 40 in a manner and for purposes hereinafter pointed out.

Fixed on the lower shaft 18 in proper position under the buttons 1, 4, and 6 are wheels 45, 46,

and 47, respectively, which have, as shown in Figure 6, diametrical lugs 48 on one side thereof, to be engaged by the lower ends of the related plunger rods 31. As indicated in Figures 2, 3 and 4, the lugs 48 of the wheels 45, 46 and 47 are displaced in position with respect to each other at intervals of 45 degrees in the starting position of the device, the lug 48 of wheel 45 being horizontal, the lug of wheel 46 being vertical, and the lug 48 of wheel 47 being angulated between these two positions.

Wires 50, 51 from the ignition circuit (not shown) can enter the casing through a grommet 52 in the casing wall 20 to connect with a pair of insulated spring contactor arms 53, 54 extending into the casing with their facing contacts 55, 55 positioned substantially in the same plane as and between the upper and lower shafts 17, 18, and in line with the position which the holes 41 and 43 in the contact masking disks 40 and 42, respectively, occupy when axially aligned. The contactor arms 53, 54 are normally spaced apart, and require to be brought together with their contacts 55, 55 in engagement, to close the ignition circuit.

Means for this purpose comprises a screw 57 threaded through a bushing 58 on the casing end wall 13 in axial alignment with the aligned position of the masking wheel holes 41 and 43. The end of the screw 57 outside of the casing 9 has an operating knob 59. The ignition circuit is closed by turning the screw 57 into the casing to pass through the aligned holes 41 and 43 in the masking disks until the screw engages the near contactor arm 53 and moves it over into engagement with the other contactor arm 53, and broken when the screw 57 is withdrawn from the contactor arm 53. The device is free to be operated by depressing the plunger heads 30 upon withdrawal of the screw 57 from the masking wheel holes 41 and 43, to the position shown in Figure 2.

The screw 57 has projecting radially therefrom between the masking wheel 42 and the ratchet dog 28 an L-shaped arm 57' which, when the screw 57 is moved to and somewhat beyond withdrawn inoperative position, moves under the ratchet dog 28 so as to raise the same from the ratchet wheel 26 and thereby permit the spring 23 to return the shaft 18 to the starting position, from which it was moved by operation of the correct combination of buttons 1-6-4, to bring the hole 43 of masking wheel 42 into alignment with the screw 57.

In the positions of the parts shown in Figures 2, 3 and 4, the combination effective to permit closing of the described lock switch is 1-6-4, that is depression of buttons 1, 6 and 4 in that order, is required to align the masking wheel holes 41 and 43 to permit effective inward movement of the screw 57.

Should any of the other buttons 2, 3 or 5 be depressed the upper shaft 17 will be given a one-eighth revolution which will put the hole 41 in masking wheel 40 out of alignment with the hole 43 in masking wheel 42 and prevent effective inward movement of the bolt 57. The only way in which the upper shaft 17 can then be returned to starting position is by the use of a key 60 passed through a guide tube 61 on the casing side wall, by means of which the dog 27 of the ratchet wheel 25 can be released from the wheel 25 so as to permit the return spring 19 to return the shaft 17 to starting position.

From the foregoing it will be evident that only

by depressing the correct combination of buttons can the switch mechanism be closed to close the circuit associated therewith, and that the only way in which the device can be restored to operable condition after the buttons have been depressed in a wrong combination is through the use of the key 60 to release the upper shaft ratchet dog 27. Therefore, without possession of the key 60 and knowledge of the correct combination, the device cannot be operated and the circuit associated with the device cannot be closed and the automobile operated and/or stolen by an unauthorized person.

What is claimed is:

15. 1. A combination lock switch comprising a casing, a pair of opposed, normally spaced insulated contact arms projecting in said casing, an axially movable closing element extending through said casing and arranged to be moved inwardly there-in to engage one of said contact arms and press the same into electrical engagement with the other contact arm to close a circuit therethrough, a pair of axially rotatable shafts mounted in said casing, each shaft having a masking disk thereon provided with an eccentric hole to pass said axially movable element to enable said element to be moved from an inoperative retracted position to an inward position in operative engagement with said one contact arm only while said 30 holes are aligned, eccentric cams spaced along each of said shafts, spring retracted plungers arranged on said casing to be selectively depressed to engage said eccentric cams to rotate at least one of said shafts into and out of positions in 35 which the holes in the masking disks are aligned, and ratchet means engaged with said shafts to retain said shafts against counter rotation after rotation produced by depression and release of selected ones of said plungers.
20. 2. A combination lock switch comprising a casing, a pair of opposed, normally spaced insulated contact arms projecting in said casing, an axially movable closing element extending through said casing and arranged to be moved inwardly there-in to engage one of said contact arms and press the same into electrical engagement with the other contact arm to close a circuit therethrough, a pair of axially rotatable shafts mounted in said casing, each shaft having a masking disk thereon provided with an eccentric hole to pass said axially movable element to enable said element to be moved from an inoperative retracted position to an inward position in operative engagement with said one contact arm only while said 45 holes are aligned, eccentric cams spaced along each of said shafts, spring retracted plungers arranged on said casing to be selectively depressed to engage said eccentric cams to rotate at least one of said shafts into and out of positions in 50 which the holes in the masking disks are aligned, and ratchet means engaged with said shafts to retain said shafts against counter rotation after rotation produced by depression and release of selected ones of said plungers.
25. 3. A combination lock switch comprising a casing, a pair of opposed, normally spaced insulated contact arms projecting in said casing, an axially movable closing element extending through said casing and arranged to be moved inwardly there-in to engage one of said contact arms and press the same into electrical engagement with the other contact arm to close a circuit therethrough, a pair of axially rotatable shafts mounted in said casing, each shaft having a masking disk thereon provided with an eccentric hole to pass said axially movable element to enable said element to be moved from an inoperative retracted position to an inward position in operative engagement with said one contact arm only while said 55 holes are aligned, eccentric cams spaced along each of said shafts, spring retracted plungers arranged on said casing to be selectively depressed to engage said eccentric cams to rotate at least one of said shafts into and out of positions in 60 which the holes in the masking disks are aligned, and ratchet means engaged with said shafts to retain said shafts against counter rotation after rotation produced by depression and release of selected ones of said plungers.
30. 4. A combination lock switch comprising a casing, a pair of opposed, normally spaced insulated contact arms projecting in said casing, an axially movable closing element extending through said casing and arranged to be moved inwardly there-in to engage one of said contact arms and press the same into electrical engagement with the other contact arm to close a circuit therethrough, a pair of axially rotatable shafts mounted in said casing, each shaft having a masking disk thereon provided with an eccentric hole to pass said axially movable element to enable said element to be moved from an inoperative retracted position to an inward position in operative engagement with said one contact arm only while said 65 holes are aligned, eccentric cams spaced along each of said shafts, spring retracted plungers arranged on said casing to be selectively depressed to engage said eccentric cams to rotate at least one of said shafts into and out of positions in 70 which the holes in the masking disks are aligned, and ratchet means engaged with said shafts to retain said shafts against counter rotation after rotation produced by depression and release of selected ones of said plungers, return spring means for returning said shafts to starting position after rotation produced by operation of selected plungers, and releasing means for releasing said ratchet means to permit operation of said return spring means.
35. 5. A combination lock switch comprising a casing, a pair of opposed normally spaced insulated contact arms projecting in said casing, an axially movable closing element extending through said casing and arranged to be moved inwardly there-

in to engage one of said contact arms and press the same into electrical engagement with the other contact arm to close a circuit therethrough, a pair of axially rotatable shafts mounted in said casing, each shaft having a masking disk thereon provided with an eccentric hole to pass said axially movable element to enable said element to be moved from an inoperative retracted position to an inward position in operative engagement with said one contact arm only while said 10 holes are aligned, eccentric cams spaced along each of said shafts, spring retracted plungers arranged on said casing to be selectively depressed to engage said eccentric cams to rotate at least one of said shafts into and out of positions in 15 which the holes in the masking disks are aligned, and ratchet means engaged with said shafts to retain said shafts against counter rotation after rotation produced by depression and release of selected ones of said plungers, return spring 20 means for returning said shafts to starting posi-

tion after rotation produced by operation of selected plungers, and releasing means for releasing said ratchet means to permit operation of said return spring means, said releasing means comprising a member on said axially movable member for releasing the ratchet means related to one shaft and a key insertible through an opening provided in said casing for releasing the ratchet means related to the other shaft.
